UNITED STATES PATENT OFFICE.

ROBERT P. SCOTT, OF CADIZ, OHIO.

GREEN-PEA-VINE-HULLING MACHINE.

1,082,609.

Specification of Letters Patent. Patented Dec. 30, 1913.

Application filed April 7, 1913. Serial No. 759,387.

To all whom it may concern:

Be it known that I, ROBERT P. SCOTT, a citizen of the United States, residing at Cadiz, Harrison county, Ohio, have invented certain new and useful Improvements in Green-Pea-Vine-Hulling Machines, of which the following is a specification.

My invention relates to green pea vine hulling machines and one of the objects of my invention is to improve the construction of such machines shown in Letters Patent Numbers 499,397 June 13, 1893 to R. P. Scott; 957,442 May 10, 1910, to R. P. Scott; 957,443 May 10, 1910 to R. P. Scott; 957,444 May 10, 1910 to T. A. Scott; 500,299 June 27, 1893 to Scott and Chisholm.

One of the objects of my invention is to improve the construction of the beaters in such machines and also the construction and arrangement of the lifting ribs, the ribs being provided with guards so as to increase the efficiency of the machine and its capacity to hull and separate peas.

In general my new pea hulling machine resembles those indicated in the patents referred to and retains intact the well established impact process. Certain faults have been discovered in the use of these machines since the invention of the Chisholms and of this applicant, especially with relation to the requirements in canned goods, in which a much higher grade and more perfection in packing are now demanded. Broken peas which disintegrate and impair the general appearance of the goods are particularly to be avoided. In order to partially overcome these difficulties, many packers have adopted what are termed tandems namely machines in which the vines are run successively through two machines. Others run the vines through the same machine twice. The expense and delay of these expedients are apparent. The tandem arrangement is required only on certain kinds of peas, which require more frequent but less severe impact.

In accordance with my invention, I find that all peas can be hulled by running them through a machine once, if it is properly adjusted, and regulated in accordance with my invention. The peas which require the mildest impact in hulling are more liable to injury by being struck after they are out of the pod. It will be seen that my improved lifting ribs greatly facilitate the sifting of

the hulled peas, so that when the vines and peas are struck, many of the hulled peas will be thrown through the inner guard upon the lifting ribs or against the solid portions of the perforated rubber screen forming the 60 wall of the drum, whereupon they roll down between the guard and the rubber screen and thereafter pass the outer edge of the lifting rib. These peas may thus be discharged upon the perforated rubber screen 65 below and will not roll inwardly off the rib, and drop upon a mass of vines or into the path of the impact beaters, and be again struck with consequent injury to the peas.

The prior machines while perfect in general principle have been too rigid in detail to suit the present exacting requirements of the trade. I find that by making the beaters of springy material, such as sheet metal, the blow given thereby to the peas is elastic 70 and yielding to some extent, with a consequent reduction in the number of broken peas. By varying the pitch angle and height of the beaters, the machine is adapted for work on different kinds of peas so as to most effectively hull them.

By sifting out the peas, instead of delivering them with the waste vines, a considerable economy is effected since the cost of peas is now much more than formerly and there is 85 particularly a demand for a more tender and perfect product. Peas are not allowed to mature as formerly and the expense of labor and handling has been increased. Owing to the delicate nature of the peas, it is desirable 90 not to retain them among the vines, long enough to reach the discharge end of the machine. In order to attain the above objects, the improved lifting rib, the guard therefor, the springy beaters and their adjustment as 95 to pitch and height, all act in combination to quickly and effectively hull the tender peas.

With the above objects in view my invention consists in the parts, improvements and combinations more fully pointed out hereinafter.

Referring now to the drawings: Figure 1 shows a front elevation of outer elevating cylinder and inner beater carrying drum. Fig. 2 shows a detailed view of my improved lifting rib. Fig. 3 shows an edge view of another lifting rib or modification. Fig. 4 shows an end view of Fig. 3. Fig. 5 shows a plan view of a lifting rib cut away 110

at the discharge end of the machine. Fig. 6 shows an edge view of spring beater. Fig. 7 shows an end view of Fig. 6. Fig. 8 is a detailed view in perspective showing peas 5 passing between the lifting rib and the screen.

Pea vine hulling machines are in almost universal use for hulling green peas from the vines and as is well known consist of a 10 frame provided with travelers supporting an outer revoluble cylinder or drum with annular ends 40. The ends of the drum are connected by elevating ribs. An inner drum or prism integral with a central shaft carries the beaters. The feed ends of both 15 drums, the lifting ribs and beaters are shown in Fig. 1. The six sides of the outer drum are covered by screens which may be of sheet metal or wire but are preferably of 20 perforated rubber, 1, Fig. 1, held in frames secured to the elevating ribs 2. The inner beater carrying drum 3 carries beaters 4 rotated by shaft 5, arranged in sets along the shaft. The rotation of the outer revoluble 25 drum and inner beater carrying drum will be assumed to be clockwise as indicated by the numerals 1^a to 12^a.

When the vines with peas attached as they come mowed in bulk from the field are 30 fed into the machine they are caught by one of the lifting ribs 2 and carried around and up to about the 11 o'clock position indicated by the numeral 11^a, when they drop off into the path of the more rapidly revolving 35 beaters 4. The beaters striking the vines throw them across to about the two o'clock position, indicated by the numeral 2^a. The foregoing operation has been common in pea vine hulling machines but it will be seen 40 that when the vines are struck and any of the peas liberated there has been but one chance of discharging the hulled peas on the two o'clock side of the machine that is if the peas would strike a perforation fairly 45 and be thrown through. Otherwise they would strike the rubber covering between the holes and drop down upon the mass of vines or be imprisoned between the vines and the upper surface of the lifting rib. That many 50 peas are thus retained inside is indicated by the fact that almost all the hulled peas are found directly under the seven o'clock position showing that the principal sifting is done as the peas and vines roll over them- 55 selves at that point. In accordance with my invention, the hulled peas are given a much better chance to get to the outside at once as they are struck and thrown across the top. That is to say, if the peas once 60 get away from the vines I do not give them a chance to get mixed up again. To do this I first put a ledge 7 along the inner side of the main rib 2 to prevent any peas from rolling off toward the center of the 65 machine, which if they do, will cause them

either to be struck again or to fall upon a mass of vines lying down on the next rib.

In accordance with my invention, the hulled peas roll upon a sifting surface which may be the perforated rubber screen forming the outside of the drum. The vines are kept from coming into contact with the rib so as not to become mixed with the hulled peas which reach the rib. The means for accomplishing this result may be varied. 70 As shown in Fig. 3, I may make use of a metal sheet 60 raised at intervals 61, upon the tops of which the vines would fall, the peas dropping down between, and rolling across the rib, after passing the three 75 o'clock position or the vines may be kept free from the hulled peas, by means of a wire screen 6 extending from an auxiliary ledge 7 mounted upon the main rib 2. The ledge 7 prevents the peas rolling inwardly toward 80 the beater carrying drum, which would happen before the main lifting rib 2 reached the three o'clock position, in which case the peas would drop into the path of the beaters and be struck again or would drop down upon the top of a mass of vines lying against a rib below. The wire net 6 may run about a half or third way along the rubber screen 85 more or less.

Another feature of my invention consists 90 in the manner of taking care of the peas when they roll to the outer edge of the lifting rib. This rib does not run out against the frame 19 of the rubber covering as heretofore, but only at places or intervals 20 100 to support the frames 19. The rib is cut away or spaced at 21 so that the peas can roll down past the outer edge, of the rib, and through to and upon the clear surface 105 of the screen below. It is important to notice that the peas cannot get off the rib until the rib has passed the three o'clock position. The screen upon which the peas then roll is in the best position for sifting purposes 110 that is to say, it lies at an angle of some forty-five degrees with no vines in the way.

One reason for having a very open wire net 6 to catch the vines is that there will be less danger of hulled peas striking a wire. Some full pods which have been detached 115 from the vines get through the wire net but are arrested by the rubber screen. These pods will drop back through the wire when at the top or roll out from between the wire and rubber at the nine o'clock position. One 120 advantage of my wire net instead of a more rigid device is its adjustability because of its pliability. There are two ways of throwing the vines out upon the beaters earlier or later as they are raised up from the bottom of the 125 outer cylinder, namely by narrowing the rib so the vines would drop or roll off quicker or by changing the slant of the rib. Now it will be seen that I cannot only adjust the 130 slant of the wire net all along the rib but I

can also adjust or change it for a part way and let the rest be different, that is to say, I can make the net of such slant at one place that the vines will drop off and be struck 5 once and at another place cause the vines to drop off earlier and be struck twice. By this means I can arrange the front part of the machine or feed end to strike the vines but once and later at the discharge end to 10 strike them twice. This adjustability is quite an advantage since some varieties of peas are much more tender and at the same time more difficult to hull. By means of this adjustable feature I can treat the peas more 15 leniently at first and at the same time so severely at the tail end of the machine that no peas will escape without being hulled. Or it may be preferable to treat the peas more leniently all the way through, which 20 can be done sometimes to great advantage by slowing down the speed of the machine and then causing the peas to be struck more often. To be able to adjust the machine quickly to any peculiar requirement is a feature 25 of great value to packers who aspire to packing the best quality of goods. The different requirements do not only occur by reason of different varieties of peas but the whole hulling system differs in different 30 years. A wet or dry season changes the conditions and the prevailing weather is apt to alter everything.

One object of the invention is to provide a beater Figs. 6 and 7, with a certain amount 35 of spring to it so as to be less hard on the peas and furthermore to make the same adjustable in their pitch. This regulates the speed with which the vines and peas pass from the feed to the discharge end of the 40 machine. This feature of my invention consists in making the beater of spring steel or of any flexible nature. The beater has a portion turned over to form a foot 22 or resting surface which is provided with elongated holes 23 so arranged that by simply 45 loosening the bolts 24 the beater can be adjusted in its slant. This controls the spiral or forward thrust against the vines feeding through the machine. In former machines 50 heavy rigid beaters were used which made a dead stroke. I have discovered that a spring stroke such as given by a piece of thin steel or a light pine shingle, opens the pods more readily and for this reason I use the spring 55 steel beater shown herein. Furthermore I have found that different peas in different seasons require a less rapid stroke and more of them. Hence with my new beater the speed can be slowed down and at the same 60 time the beater put straighter or more parallel with the central shaft through the drum so as to hold the vines in the machine longer. Another adjustment I use is to increase the 65 height of the beater or rather increase its radial length from the center of the shaft or

drum which carries the beaters. This is accomplished by bolts 25 and slots 26 which adjust the ends 27 of the beater. It will be seen by this last arrangement the beaters can be set not so far out at the beginning or feed end and then farther out nearer the exit end. By this means the peas receive a harder or more rapid stroke toward the last and thus if any pods are of very tough or resisting nature, they will be opened before 70 they get clear of the machine and that without an equally severe treatment at the start. As the beaters must not come too close to the lifting ribs and if it is desired to extend them to a greater height radially the lifting 75 rib may be made of varying width. In the form of the invention illustrated, the rib is cut away at 28 as shown in Fig. 5, so as to receive the beater of greatest height without decreasing the clearance between said beaters and the adjacent portion of the lifting rib. Moreover the narrow portion of the lifting rib will begin to let the peas drop earlier in the revolution, that is to say at 80 about seven or eight o'clock position, upon 85 or into the path of the beaters. Therefore when struck they are thrown to the eleven or twelve o'clock position. They then drop again and are struck thus making a double stroke in each round of the lifting ribs 90 thereby making a further certainty of all 95 the peas being hulled before passing out of the machine, but not faster than the sifting action is taken care of.

I have found it quite important that the 100 machines are adjustable in several ways to accommodate different conditions and since the pea season is very short all adjustments must be made quickly.

It will be seen that by changing the slant 105 of the net or screen 6 I avoid making the rib 2 adjustable in width which would accomplish the same purpose.

The operation of my improved machine 110 will be apparent from the above description.

Having thus fully described the construction and arrangements of the several parts of my improved machine for hulling and separating green peas upon the vines, what I claim as new is:

1. In a pea vine hulling machine, a lifting rib, a guard mounted upon the face of said rib having a portion suitably spaced, therefrom, said guard preventing the hulled peas from rolling off the rib toward the impact beaters and means permitting the discharge of the hulled peas from the rib, said means being located at the outer edge of the rib.
2. In a pea vine hulling machine, a lifting rib, an auxiliary ledge for said rib so arranged with relation thereto as to prevent the hulled peas from rolling inward upon the beaters.
3. In a green pea vine hulling machine 130

- working on the impact principle, a lifting rib provided with means for permitting the hulled peas to be disposed of at the outer edge of the rib, in combination with a guard 5 for said rib.
4. In an impact pea hulling machine, the combination of a lifting rib, an auxiliary ledge thereon, and a wire guard extending across the rib and along the outer screening 10 surface, said guard being spaced from said rib and from said surface.
5. In a pea vine hulling machine, a central shaft carrying a plurality of impact beaters which are arranged in sets along the shaft, 15 a lifting rib of varying width coöoperating therewith, one set of beaters arranged opposite the narrow portion of the lifting rib, said set being adjustable so as to vary the radial length of the beaters and determine 20 the clearance between said set of beaters and the adjacent portion of the lifting rib.
6. In a pea vine hulling machine, a lifting rib and an adjustable guard extending over the face of the rib.
7. In a pea vine hulling machine, a drum, 25 impact beaters carried thereby, said beaters being made of flexible, springy material so as to permit the peas to be hulled with elastic blows and a lifting rib for dropping vines 30 into the path of said beaters and a plurality of rotary lifting ribs for delivering said peas to said beaters.
8. In a pea vine hulling machine, a central shaft carrying a plurality of impact 35 beaters which are arranged in sets along the shaft, and a lifting rib of varying width coöoperating therewith, one set of beaters arranged opposite the narrow portion of the lifting rib.
9. In a pea vine hulling machine, a shaft, 40 a plurality of impact beaters arranged in sets along said shaft, one or more of said beaters being adjustable in a radial direction toward and from the shaft, independently
- of the other beaters and a lifting rib for 45 delivering the vines to said beaters.
10. In a pea vine hulling machine, a shaft, a plurality of sets of beaters carried by said shaft, means for adjusting one of said beaters radially toward and from the shaft independently of the other beaters and means for adjusting said beater so as to vary its pitch with relation to the shaft. 50
11. In a pea vine hulling machine, a springy impact beater adjustable as to its 55 pitch and as to its height and a lifting rib for delivering peas to said beater.
12. In a pea vine hulling machine, a shaft, spring beaters carried thereby, lifting ribs and guards for said ribs. 60
13. In a pea vine hulling machine, the combination of a plurality of guarded lifting ribs and a plurality of adjustable beaters carried by the shaft of the machine for impacting the vines delivered by said ribs. 65
14. In a pea vine hulling machine, a shaft, a plurality of lifting ribs varying in width and a plurality of springy adjustable beaters carried by said shaft. 70
15. In a pea vine hulling machine, the 75 combination of lifting ribs varying in width, a plurality of adjustable guards for said ribs, a shaft and a plurality of springy, adjustable impact beaters carried by said shaft.
16. In a green pea vine hulling machine working on the impact principle the combination of a lifting rib provided with an opening constructed to permit the passage of peas therethrough and a guard for said 80 rib.

In testimony whereof, I have signed my name to this specification, in the presence of two subscribing witnesses.
